Moulton B. Taylor, 1320 Hudson St., Longview, Wash.

Filed Jan. 2, 1958, Ser. No. 49,093

Term of patent 14 years

(Cl. D71—1)

FIG 2FIG 3

FIG. 1 is a side perspective view, taken slightly from the front, of an aeroplane embodying my new design;

FIG. 2 is a top plan view thereof drawn to a smaller scale; and

FIG. 3 is a front view of the aeroplane on the same scale as FIG. 2.

The side of the aeroplane not shown, is substantially the same in appearance as the side shown as indicated in FIGS. 2 and 3.

I claim:

The ornamental design for an aeroplane, substantially as shown and described.
